UNITED STATES PATENT OFFICE.

AARON COHN, OF TORONTO, ONTARIO, CANADA.

EYE-SUPPORTING UNIT FOR DOLLS.

Application filed May 1, 1925. Serial No. 27,202.

To all whom it may concern:

Be it known that I, AARON COHN, a citizen of the United States of America, resident of the city of Toronto, in the Province of Ontario, in the Dominion of Canada, have invented new and useful Improvements in Eye-Supporting Units for Dolls, of which the following is a specification.

The invention relates to improvements 10 in eye-supporting units for dolls as described in the present specification and shown in the accompanying drawings which form part of the same.

Whereas various eye-supporting units 15 exist for the mounting of movable eyes within a doll's head, amongst which may be mentioned a patent granted to me on the 30th of December, 1924, No. 1,521,279, for "sleeping dolls' heads". In this patent 20 structure disclosed is only applicable to dolls' heads having crown apertures through which the eye unit is inserted and hair subsequently applied to cover such apertures.

This structure has been found to be impracticable for dolls in which the hair is molded or otherwise made an integral part of the head itself on account of the interior of such a doll's head being only accessible through the neck opening.

30 The object of the present invention is to devise an eye-supporting unit which may be mounted in the head by inserting through such neck opening, in such a manner as to be economical in manufacture and 35 efficient in its use.

The invention consists substantially of a bridge for sustaining the eyes in their sockets and a support for such a bridge so arranged that it may be inserted through 40 the neck opening and secured to the head.

Referring to the drawings: Figure 1 is a vertical sectional view of a doll's head embodying the invention.

Figure 2 is a similar view thereof illustrating the manner of fitting the bridge in its mounting within the head.

Figure 3 is a perspective view of the bridge support.

Figure 4 is a fragmentary view of the 50 head showing a slightly modified form of bridge support.

Figure 5 is a further modified form of the invention showing the manner of sustaining the bridge entirely by the vertical support.

Like numerals of reference indicate cor-

responding parts in each figure throughout the drawings.

In the drawings, the reference numeral 1 indicates the head of the doll, which is 60 hollow and moulded in one-piece, 2 designates the neck opening leading into the head interior; 3 are the spherical eyes, adapted upon oscillation, to simulate the opening and closing of an eye. These eyes 65 are supported upon a shaft 4 to which they are centrally affixed, said shaft constituting the axis about which they rotate. 5 is the customary pendulum for the gravity actuation of doll's eyes.

Whilst the aforementioned description of the movable eye structure is a typical illustration of such doll's eye-structures, it is, of course, understood that this particular form of construction does not in any 75 way form a part of the present invention, and the invention itself, as hereinafter disclosed, may be applied to movable eyes of varying structures.

6 is the bridge, which consists of a bar 80 extending horizontally, the forward end of which is bent back upon itself in order to form a slot 7 which receives the shaft 4. The rear end of this return-bend rises vertically for a short distance as at 8 and carries a spring 9 having a pair of downwardly turned arms straddling the bridge and outwardly urging the shaft 4 so as to retain the eyes resiliently in their sockets.

The frontal extremity 10 of the bridge is 90 sustained in the head by inserting it in an indenture 11. Manifestly, however, this could be effected by providing a prong, or prongs, for embedding in the wall of the head at this point, if so desired.

The opposing end of such bar is bent downwardly from a point 12 so as to form an integral extension 13. 14 is the bridge support, which is rigidly embedded in the top of the head by a prong 15 extending in the direction of its length, and similarly attached to the base of the head in the proximity of its neck by a further prong 16, which is bent normal to the length of such member. The said support is provided with flanges 17 which form a channel section guide receptive to the extension 13 of the bridge, which bridge is retained in such guide by a projection 18 that abuts the bight 12, and a further projection 19 bent 110 over the lower extremity of such extension.

To mount the eye-supporting unit in the

head, the bridge support 14 is inserted vertically through the neck opening and its prong 15 pressed into position. The lower end is then attached to the neck by firmly embedding its prong 16 in the wall thereof. It will be observed that this construction greatly facilitates securing of the support in the head by reason of the fact that such support can be gripped by a pair of pliers to insert its upper prong in place by merely pressing or pushing upon it lengthwise. It is then a simple matter to press the prong of the lower end into place as on account of the neck opening the pliers can be easily handled at this point for this purpose.

The eye unit together with its bridge is then placed by inserting same upwardly through the neck opening and the eyes fitted in their sockets, the forward end of the bridge 10 being fitted in the indenture 11, while the rear end is slid up the channel of the bridge support 14 until the bight 12 is encountering the stop or projection 18, the extension 13 then lying contiguous with the lower portion of the bridge support. This extension is then securely attached by merely bending over the projection 19 in order to grip its lower extremity.

Referring to Fig. 4, this shows a variation of a bridge support consisting of two parts, one at right angles to the other, the lower portion which supports the bridge being in all ways identical to that aforescribed and being likewise similarly embedded by a prong in the vicinity of the neck, while the other part 20 has a similar prong for embedding in the back of the head so as to directly sustain the horizontal thrust of the bridge.

Figure 5 shows a still further modification, in which the bridge is entirely carried by a vertical support, dispensing with supporting connections at the frontal end 10 of the bridge. In this view 21 is the vertical bridge support and 22 the bridge having an extension 23 perpendicular therewith similar to the extension 13 of the preferred form. The upper end of this extension is provided with a lug 24 that is inserted into a hook 25 or downwardly curved prong, while its lower end is fastened by a projection 26 similar to the projection 19.

What I claim is:

1. The combination with a hollow doll's

head having an opening through the neck, of a pair of eyes, a bridge for retaining said eyes in their sockets consisting of a horizontally extending bar having a downwardly turned extension at its rear, the wall of the aforesaid head having an indenture provided in its forward portion receiving the frontal extremity of said bar, a substantially upright bridge support, means for attaching the support to the wall of the head, a shoulder formed on said support for abutment with the bight of the extension, and a projection for bending over its lower end.

2. The combination with a hollow doll's head having an opening through the neck, of a pair of eyes, a bridge for retaining said eyes in their sockets consisting of a horizontally extending bar having a downwardly turned extension at its rear, the wall of the aforesaid head having an indenture provided in its forward portion receiving the frontal extremity of said bar, a substantially upright bridge support, means for attaching the support to the wall of the head, a guide constructed integrally with said support for receiving the bridge extension, a shoulder formed on said support for abutment with the bight of the bridge, and a projection for bending over the lower end of the extension.

3. The combination with a hollow doll's head having an opening through its neck, of a pair of eyes, a bridge for retaining said eyes in their sockets consisting of a horizontally extending bar having a downwardly turned extension at its rear, the wall of the aforesaid head having an indenture provided in its forward portion receiving the frontal extremity of said bar, a vertical bridge support terminating at its upper end in a lengthwise prong for embedding in the crown of the head and terminating in a further prong at its lower end for embedding in the wall of the neck opening, flanges forming a lengthwise guide integral with said support receiving the bridge extension, a projection for abutting the bight of the extension, and a projection bent over its lower end.

Signed at the city of Toronto, in the Dominion of Canada, this 27th day of April, 1925.

AARON COHN.
